(57) **CLAIM**

The ornamental design for a casing for lighting equipment, as shown and described.

DESCRIPTION

FIG. 2.1 is a front view of the casing for lighting equipment embodying our new design;

FIG. 2.2 is a rear view thereof;

FIG. 2.3 is a top view thereof;

FIG. 2.4 is a bottom view thereof;

FIG. 2.5 is a right side view thereof;

FIG. 2.6 is a left side view thereof;

FIG. 2.7 is a perspective view thereof;

FIG. 2.8 is a top detail view thereof;

FIG. 2.9 is a sectional detail view thereof;

FIG. 2.10 is a bottom detail view thereof; and

FIG. 2.11 is a right side detail view thereof.

The broken lines in the drawings are by way of illustration only and form no part of the claimed design.
